COMBINATION STEERING POST AND INSTRUMENT PANEL

Darrell C. Fuller, Niles, Mich., assignor to
Clark Equipment Company

Filed Dec. 3, 1970, Ser. No. 26,264

Term of patent 14 years

Int. Cl. D12—16

U.S. Cl. D14—6

FIG. 1

FIG. 2

FIG. 3

FIG. 4

FIG. 5

FIG. 6

FIG. 7

FIG. 8

FIG. 9

FIG. 10

FIG. 1 is an elevated right rear quarter perspective view of a combination steering post and instrument panel for a vehicle showing my new design;

FIG. 2 is an elevated rear perspective view thereof;

FIG. 3 is a right front quarter perspective view thereof;

FIG. 4 is a right side perspective view thereof;

FIG. 5 is an elevated left rear quarter perspective view thereof;

FIG. 6 is an elevated right rear quarter perspective view of a modified form thereof;

FIG. 7 is an elevated rear perspective view of FIG. 6;

FIG. 8 is an elevated right front quarter view thereof;

FIG. 9 is a right side perspective view thereof; and

FIG. 10 is a left rear quarter perspective view thereof.

The portions shown in broken lines are shown for illustrative purposes only.

I claim:

The ornamental design for a combination steering post and instrument panel, as shown and described.
